CLAIM

The ornamental design for a combined mirror and
clock, substantially as shown and described.

DESCRIPTION

FIG. 1 is a perspective view of a combined mirror and
clock showing one embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a cross-sectional view thereof taken along line
8—8 in FIG. 2.

FIG. 8

FIG. 1

FIG. 2

FIG. 3

FIG. 4
